ELECTRIC TERMINAL RECEPTACLE

Ernest E. Sutherland, Mansfield, Ohio, assignor
to Westinghouse Electric Corporation, East
Pittsburgh, Pa., a corporation of Pennsylvania

Application September 30, 1943, Serial No. 504,371

5 Claims. (Cl. 173—332)

1

This invention relates to heating apparatus and particularly to a terminal receptacle for electric range heating elements and the like, and it has for an object to provide an improved device of the character set forth.

It is another object of the invention to provide an improved terminal receptacle having spring-biased contact-carrying members in which the springs may be readily replaced or repaired.

It is also an object of the invention to provide an improved terminal receptacle in which the contacts may be readily replaced or repaired.

These and other objects are effected by the invention as will be apparent from the following description and claims taken in connection with the accompanying drawings, forming a part of this application, in which:

Fig. 1 is a side elevational view of an electric range in which the invention has been incorporated, the central portion of the range being broken away along substantially the vertical center of the range oven;

Fig. 2 is a sectional view taken substantially along the line II—II of Fig. 1 and showing the terminal receptacle in plan;

Fig. 3 is a sectional view taken substantially on the line III—III of Fig. 2; and

Fig. 4 is an end elevational view of the terminal receptacle, looking at the end of the receptacle which is disposed in the oven.

While not limited thereto, the terminal receptacle of the present invention is particularly adapted for use with the removable oven heating elements of electric ranges as shown in Fig. 1 of the drawings. The range shown in Fig. 1, and generally indicated 10, may be of conventional construction including a body 11 and a cooking platform 12 having the usual surface cooking units 13. The body 11 is provided with a heat-insulated oven 14 accessible by means of a door 15.

The oven is heated by means of upper and lower electric heating elements 16 and 17, respectively. The heating elements may be of any suitable construction and slidably supported on the top and bottom walls of the oven so that they may be readily removed for repair and to facilitate cleaning of the elements and of the oven. The heating elements 16 and 17 differ from conventional oven elements in that their terminal rods 18 are preferably provided with electrical contacts 19 which engage cooperating contacts 20 of a terminal receptacle 21 for connecting the heating elements in electrical energizing circuits when inserted in the range oven.

2

Both terminal receptacles 21 are identical and a description of one will suffice. Each receptacle comprises a block 22 of insulating material having a flange 23 formed integrally therewith. The forward end 24 of the block is received in an opening 25 in the rear wall 26 of the oven and the block is secured to this wall by means of bolts 27 which extend through openings provided in the rear oven wall and openings provided in the flange 23, as shown in Fig. 2.

In the particular embodiment of the invention illustrated, the heating elements each have three terminal rods 18 and contacts 19 adapted to engage the three contacts 20 mounted in the terminal receptacle 21. Each contact 20 is carried on an L-shaped bar 31 which is slidable in a hole 32 extending longitudinally through the block. The forward end of the hole 32 is enlarged, as indicated at 33, to receive the upwardly turned end 20 of the bar 31 and the terminal rod 18 and its contact 19, as shown in Fig. 3.

In order to insure proper contact pressure between the contacts 19 and 20, a spring 34 is secured to the contact-carrying bar 31 by means of a screw 35. An opening 36 extending normal to and communicating with the hole 32 provides access to the screw 35. The flat rear wall 37 of the opening 36 serves as an abutment for the spring 34, so that the spring biases the contact bar 31 to the right, as viewed in Fig. 3, and permits the contact bar to yieldingly resist displacement by the terminal rod 18 as it is inserted in the terminal receptacle, insuring adequate contact pressure between the contacts 19 and 20.

35. A terminal strap 38, secured by means of the screw 35 to the contact bar 31, extends through the hole 32 to the rear of the block 22. This strap is provided with a screw 39 for clamping an electrical supply conductor 41, as shown in Fig. 1, to the terminal straps.

It will be noted that the terminal block projects through an opening 42 provided in a rear panel 43 of the range body, and that the vertical opening 36 in the block and the screw 35 and spring 34 therein are accessible at the rear of this panel 43. By virtue of this arrangement, it is possible to repair or replace the spring 34 by merely removing the screw 35 without in any way disturbing the connection of the supply conductors 41 or the terminal block itself. This arrangement also permits the contact bar 31 to be replaced, in the event that its contact 20 is damaged, without the necessity of disconnecting the supply conductors 41. Thus the spring 34 and the contact bar 31 may be removed and new ones substituted by

merely removing the screw 35 and lifting the spring 34 upwardly through the opening 36 and withdrawing the contact bar 31 into the oven and these parts replaced by merely reversing the steps just enumerated. The noncircular portion 36a of the opening 36, which includes the flat wall 37, retains the spring 34 in position as the screw 35 is tightened.

While the contact bar 31 and terminal strap 38 have been disclosed as separate members, it is to be understood that they may comprise a single strip of metal or two strips as shown, permanently secured together at their overlapping portions.

While the invention has been shown in but one form, it will be obvious to those skilled in the art that it is not so limited, but is susceptible of various changes and modifications without departing from the spirit thereof, and it is desired, therefore, that only such limitations shall be placed thereupon as are specifically set forth in the appended claims.

What is claimed is:

1. A terminal receptacle for use with an electric heater or the like comprising a block of insulating material having an opening extending therethrough, said block having a second opening therein disposed at an angle to and communicating with the first-mentioned opening, a contact-carrying bar received in the first-mentioned opening and movable longitudinally therein, and a spring member secured to said bar and received in the second-mentioned opening, said spring member engaging a wall of the second-mentioned opening and biasing said bar in one direction whereby said bar may be moved in the opposite direction against the bias of said spring member to provide suitable contact pressure between the contact carried by said bar and a terminal inserted in the receptacle.

2. A terminal receptacle comprising a block of insulating material having an opening therethrough, a rigid conductor slidably received in said opening, a contact carried by said conductor in a position to be engaged by a terminal inserted in said receptacle, a spring member engaging said block and biasing said conductor in a direction to resist movement of said conductor by said terminal on insertion of the latter into the receptacle to provide suitable contact pressure between the terminal and said contact, said spring member being detachably secured to said conductor by means accessible from the exterior of the block.

3. A terminal receptacle comprising a block of insulating material having a recess therein, a rigid conductor slidably received in said recess, an electrical contact carried by said conductor in a position to be engaged by a terminal of a

heating element or the like, a terminal strap detachably secured to said conductor, a spring member detachably secured to said conductor and biasing said conductor in a direction to yieldingly resist movement by a terminal moved into engagement with said contact to provide suitable contact pressure between the terminal and said contact, and common securing means for securing said spring and said terminal strap to said conductor.

5. A terminal receptacle comprising a block of insulating material having a recess therein, a rigid conductor slidably received in said recess, an electrical contact carried by said conductor in a position to be engaged by a terminal of a heating element or the like, a terminal strap detachably secured to said conductor, a spring member detachably secured to said conductor and biasing said conductor in a direction to yieldingly resist movement by a terminal moved into engagement with said contact to provide suitable contact pressure between the terminal and said contact, and common securing means for securing said spring and said terminal strap to said conductor, said block having an opening therein providing access to said common securing means.

10. A terminal receptacle comprising a block of insulating material having an opening therethrough, a rigid conductor slidably received in said opening, a contact carried by said conductor adjacent one end of said opening, and a spring member detachably secured to said conductor adjacent the other end of said opening, said spring member engaging said block to bias said conductor in a direction to yieldingly resist movement by a terminal moved into engagement with said contact to provide suitable pressure between the terminal and said contact, said contact and said conductor being removable from said opening at 15 said one end, and said spring member being accessible from said other end of said opening.
